UNITED STATES PATENT OFFICE

URBANO PINEDA AND TIOFILO L. ANABISA, OF SAN FRANCISCO, CALIFORNIA, AS
SIGNORS OF ONE-HALF TO SAID PINEDA, ONE-FOURTH TO SAID ANABISA, AND
ONE-FOURTH TO FELOMINO V. LANGLANG, ALL OF SAN FRANCISCO, CALIFORNIA

COMPASS

Application filed January 12, 1932. Serial No. 526,180.

Our invention relates to improvements in compasses, and it consists of the combinations, constructions and arrangements hereinafter described and claimed.

5 An object of our invention is to provide a compass, which is especially designed to be attached to a fountain pen or pencil and which, in closed position, will occupy little space so that a cap can enclose the compass. 10 The outer diameter of the cap is preferably the same as the outer diameter of the pen or pencil, so that the device will resemble a standard pen or pencil when the cap encloses the compass. It is obvious that the compass 15 can be secured to a holder if it is not desired to have it connected to a pen or pencil.

A further object of our invention is to provide a device of the type described, which is extremely simple in construction and which 20 is durable and efficient for the purpose intended.

Other objects and advantages will appear in the following specification, and the novel features of the device will be particularly 25 pointed out in the appended claims.

Our invention is illustrated in the accompanying drawing forming a part of this application, in which

Figure 1 is a side elevation of the device 30 shown operatively applied to a pen, the cap for the compass being shown in section;

Figure 2 is a similar view, with a compass cap and pen cap removed;

Figure 3 is a section along line 3—3 of Figure 2; and

Figure 4 is a section along line 4—4 of Figure 2.

In carrying out our invention, we make use 40 of the barrel 1 of a standard fountain pen or pencil, or the barrel 1 may be merely a holder. Figure 3 shows the end of the barrel 1 as being threaded at 2 for removably receiving a cap 3, shown in Figure 1. An insert 4 is placed in the open end 5 of the barrel 1 and rests upon a shoulder 6. The insert is preferably cemented in place, although it may be threaded into position if desired.

The insert 4 has a square opening 7 for receiving the square end 8 of a screw 9. The upper end of the screw is bifurcated at 10

and receives a pin 11, which, in turn, pivotally carries a compass indicated generally at 12. The compass has a pointed member 13 which has cam portions 14 pivotally secured to the pin 11 and contacting with a knurled nut 15. 55 The compass 12 also has a pencil or pen member 16 which is provided with cam ends 17 that are also pivoted to the pin 11 and bear on the nut 15. A spring 18 passes around the pin 11, (See Figure 3), and bears against the members 13 and 16 so as to urge the members 60 from the position shown in Figure 1 into that shown in Figure 2.

From the foregoing description of the various parts of the device, the operation 65 thereof may be readily understood.

When it is desired to use the compass, the cap 3 is removed and then the nut 15 is actuated so as to permit the spring 18 to move the members 13 and 16 into the desired position. The nut 15, when turned in one direction, permits the spring 18 to move the members 13 and 16 into open position and when turned in the opposite direction, engages with the cams 14—14 and 17—17 for swinging the 75 compass members toward each other. It should be noted that the outer diameter of the cap 3 is the same as the outer diameter of the barrel 1.

The fountain pen or pencil may be used in 80 the ordinary manner after first removing the cap 20. A clip 21 is carried by the cap for the purpose of supporting the device when closed in the pocket. If a pencil is used, the cap 20 would be dispensed with and the clip 21 85 would be secured to the cap 3. If the barrel 1 constitutes merely a holder without the provision of a pen or pencil, the cap 20 would be dispensed with and the barrel could then be used for housing leads and erasers, if desired. 90

While we have shown only the preferred form of our invention, it should be understood that various changes or modifications may be made within the scope of the appended claims without departing from the spirit 95 of the invention.

We claim:

1. In combination, a holder, an insert carried by the holder and having a square opening, a screw having a square head received in 100

the opening and a bifurcated end, compass members having cam-shaped portions, a pin for pivotally securing the portions to the bifurcated end, a knurled nut mounted on the screw, and a spring disposed in the bifurcated member and having its ends bearing against the compass members for causing the cam portions to contact with the nut.

12. In combination, a holder, an insert carried by the holder and having a square opening, a screw having a square head received in the opening and a bifurcated end, compass members having cam-shaped portions, a pin for pivotally securing the portions to the bifurcated end, a knurled nut mounted on the screw, a spring disposed in the bifurcated member and having its ends bearing against the compass members for causing the cam portions to contact with the nut, and a cap for receiving the compass members when the latter are in closed position, said cap being removably secured to the holder.

13. In combination, a cylindrical holder constituting a handle, a threaded shank of less diameter than the holder and being carried thereby, a nut of less diameter than the holder and being mounted on the shank, compass members pivoted to the shank and having cam portions bearing against the nut, spring means for holding the cam portions of the compass members against the nut, and a cap of the same outer diameter as the outer diameter of the holder and being removably carried thereby, said cap housing the compass members, nut and shank when the compass members are in closed position.

URBANO PINEDA.
TIOFILO L. ANABISA.
